United States Patent

Des. 241,720

Patented Oct. 5, 1976

241,720

DISPLAY PACKAGE

Rolf A. Sanning, Braintree, Mass., assignee to
The Gillette Company, Boston, Mass.

Filed Feb. 18, 1975, Ser. No. 550,559

Term of patent 14 years

Int. Cl. D9—03

U.S. Cl. D9—191

Fig. 1

Fig. 2

Fig. 3

Fig. 4

FIG. 1 is a perspective view of a display package showing my new design;

FIG. 2 is a top plan view thereof, the bottom being substantially flat and unornamented;

FIG. 3 is a side elevational view thereof, the opposite side being substantially a mirror image thereof; and

FIG. 4 is an end elevational view thereof, the opposite side being substantially a mirror image thereof.

I claim:

The ornamental design for a display package, substantially as shown and described.
